United States Patent Office

Des. 196,665
Patented Oct. 22, 1963

196,665

TRAY

Benjamin G. Barnett, 4407 Brookview, Dallas, Tex.

Filed May 27, 1963, Ser. No. 75,089

Term of patent 14 years

(Cl. D44—10)

FIGURE 1 is an isometric view of a tray showing my new design with the support element in flexed condition;
FIGURE 2 is a side elevation of the tray;
FIGURE 3 is a top plan view of the tray;
FIGURE 4 is a bottom view of the tray;
FIGURE 5 is an end elevation of the tray; and,
FIGURE 6 is an isometric view, on a smaller scale, showing the support element in unflexed condition.

I claim:

The ornamental design for a tray, substantially as shown.
